UNITED STATES PATENT OFFICE.

CLARENCE M. DAVISON, OF BALTIMORE, MARYLAND, ASSIGNOR TO POOLE ENGINEERING & MACHINE COMPANY, OF BALTIMORE, MARYLAND, A CORPORATION OF MARYLAND.

PORTABLE PRIMING DEVICE.

Application filed June 20, 1924. Serial No. 721,278.

To all whom it may concern:

Be it known that I, CLARENCE M. DAVISON, a citizen of the United States, residing at Woodberry Station, city of Baltimore, 5 and State of Maryland, have invented certain new and useful Improvements in Portable Priming Devices; and I do hereby declare the following to be a full, clear, and exact description of the same, reference being 10 had to the accompanying drawings, forming part of this specification.

This invention relates to priming devices and particularly to portable primers for internal combustion engines.

15 The rates of insurance companies for insurance on internal combustion engines vary according to the nature of the motive fluid used in the engine; the rates on engines using gasoline, for instance, being considerably 20 higher than those on engines using the lower hydrocarbons, such as kerosene. For this reason, the present invention seeks to provide a primer in which gasoline may be used as the priming charge but in which, 25 due to certain novel features of construction, the vapor of the gasoline, combined with the proper proportion of air, will be fed to the combustion chamber only for a few moments during the priming of the engine.

30 No gasoline in its liquid state can possibly reach the normal motive fluid passage of the engine or the combustion chamber thereof.

These novel features consist principally in 35 constructing the primer so that it cannot possibly be filled or recharged with gasoline while the engine is running and it cannot be overcharged,—that is, it is so constructed that any excess gasoline that may be deposited in the primer will be immediately 40 drawn off or wasted. Under these circumstances, no gasoline, in liquid form, can possibly reach the combustion chamber while the latter is in operation because only a small quantity of gasoline can be placed 45 in the primer and when the primer is put into use no more gasoline can be deposited in it without removing it from the engine which in the present invention will result in the operation of the engine being 50 stopped.

With these and other objects in view the invention consists in certain novel details of construction and combinations and arrangements of parts, all of which will be

hereinafter more fully described and the 55 novel features thereof particularly pointed out in the appended claims.

The accompanying drawings consist of a figure, a vertical sectional view, illustrating a portion of an internal combination engine 60 having a primer attached thereto, the primer shown, embodying the preferred construction contemplated by the present invention.

A portion only of the engine structure 65 proper is shown, and this more or less conventionally. The usual motive fluid supply duct 10 is shown in section with an arrow indicating the direction of flow therefrom to the combustion chamber of the engine. 70 Preferably there is an overhanging flange 11, or the like, at the side of the engine for the attachment of the primer, the under face of said projection being formed with an annular recess 12 which communicates with 75 said duct 10 by means of a short piece of piping 13 secured at its ends in the engine and in an aperture 14 in the flange. As will be presently described, the primer is secured to said flange and the priming vapors 80 escaping or discharged from the primer flow through the pipe 13 to the duct 10 where they commingle with the motive fluid or are conveyed to the combustion chamber.

The primer in the preferred form illustrated comprises an elongated cylindrical body or casing 15 adapted to be filled with a suitable absorbent material 16 that will take up or become saturated with priming fluid, usually gasoline, that is poured or deposited in the primer through the open end 17 thereof. Usually, the size of the primer body is such that of about a gill of gasoline will be required to completely saturate the material 16, this quantity having been 90 found sufficient to run the engine for about three minutes. For supplying air to the gasoline vapors that will be discharged from the primer to the duct 10 there is a 95 comparatively small opening formed in the opposite end of the primer body and a tube or other passage 18 leading from said opening is provided in the absorbent material, said passage extending preferably more than half way the length of the body and 100 back upon itself to a point where it terminates in the material immediately above its entrance end.

It will be noted that the recess 12 in flange 11 and the open end portion of the primer are each of frusto-conical shape, the end of the primer fitting tightly in said recess when 5 it is attached to the engine for use. The primer is detachably secured on the engine by any desired means such as a snap fastener in the form of a ball 19 on the body 15 that extends over the flange 11 and snaps 10 into a recess in said flange. If the primer has been charged and is in place as shown it is apparent that air will be sucked in through passage 18 and through the material 16, and that air and the vapors from 15 the gasoline, as a firing mixture, will be sucked through the pipe 13 and duct 10 to the combustion chamber of the engine.

With the primer constructed and arranged as described it cannot be filled while 20 the engine is running because to fill it, it must be removed from recess 12 in which event pure air will flow through the then unrestricted pipe 13 in such quantities as to kill the engine. A further advantage 25 of this primer is that an excessive quantity of fluid cannot be placed therein because any excess will be siphoned off (out) due to the fact that the interior end of pipe 18 terminates above the outer end thereof. 30 Thus more gasoline than is normally necessary for one priming of the engine cannot be deposited in the primer and this being true there is no possibility of the engine being operated for any appreciable length 35 of time with gasoline as its operating motive fluid. This, and the fact that the primer cannot be filled while the engine is operating under its normal motive fluid, renders the primer acceptable to the underwriters so that they do not increase their 40 rates of insurance on the lower hydrocarbon engines when this type of primer is employed. As a rule, the insurance companies have charged their gasoline engine 45 rates to owners of low hydrocarbon engines when the latter are provided with gasoline primers but as the primer perfected by applicant and claimed herein has met with the approval of the underwriters, such owners of engines using the lower hydrocarbons 50 receive the benefit of the lower insurance rates.

What is claimed is:—

1. In combination with the motive fluid supply duct of an internal combustion engine, a primer having an opening for depositing the priming fluid therein, means for attaching the primer to the engine, means for conveying the priming charge 55 from the primer to said duct, the filling opening in the primer being accessible only when the primer is detached from the engine.

2. In combination with the motive fluid 60 supply duct of an internal combustion en-

gine, a primer having an opening for depositing the primer fluid therein, and through which the priming charge is discharged, means for attaching the primer to the engine, and a relatively large passage 70 communicating with the fluid supply duct and said opening in the primer, the opening in the primer being accessible only when the primer is detached from the engine and said passage open to the air whereby the mixture supplied to the engine through the passage, when the primer is detached, will be such as to render the engine inoperative. 75

3. A primer for internal combustion engines comprising a body adapted to contain the priming charge, said body having an air passage communicating with the interior of the body adjacent one end of the latter and with the exterior of said body and there being an opening in the opposite end of the body for filling the primer and through which the priming charge may be drawn into the engine, and means for supporting the primer with its discharge opening in communication with the motive fluid supply system of the engine, the opening for filling the primer being inaccessible when the primer is attached to the engine. 80

4. A primer for internal combustion engines comprising a body having an opening through which the primer is charged and discharged, means for supporting the primer with said opening communicating with the engine cylinder, said charging opening 100 being inaccessible when the primer is attached to the engine whereby the primer must be removed from the engine for filling, and means for supplying air to the interior of the primer. 105

5. A primer for internal combustion engines comprising a body having an opening at one end through which the priming fluid is deposited in the primer and through which the priming charge is drawn to the engine, an absorbent material within the body, and an air duct leading from the exterior of the primer and terminating in the interior thereof adjacent the end opposite the filling opening whereby air coming through the duct will be drawn through the absorbent material, and means for detachably securing the primer to the engine with the charging opening end thereof up- 110 permost. 115

6. A portable primer for internal combustion engines comprising a body having an opening at one end for charging the primer, an absorbent material within the body, an air vent leading from the exterior of the body and terminating on the interior at the end thereof opposite the end provided with the charging opening, and means for attaching the body to the engine with the charging opening positioned above the air 120 125 130

vent and its terminals, whereby excess priming fluid deposited in the primer will escape through the air vent.

7. A portable primer for internal combustion engines embodying a body having one end open for depositing priming fluid therein and through which the priming vapors are discharged, a filler of absorbent material within the body, said body having

an air passage in its opposite end extending 10 up through the absorbent material and then downwardly and terminating in the filler adjacent said opposite end, whereby air drawn through the air passage at one end of the body must pass through the entire 15 filler to reach the discharge opening at the opposite end of the body.

CLARENCE M. DAVISON.
